UNITED STATES PATENT OFFICE.

JAMES O. WATKINS, OF SAN FRANCISCO, CALIFORNIA, ASSIGNOR TO FEDERAL TELEGRAPH COMPANY, OF SAN FRANCISCO, CALIFORNIA, A CORPORATION OF CALIFORNIA.

WIRELESS TELEGRAPHY.

1,224,343.

Specification of Letters Patent.

Patented May 1, 1917.

Application filed July 28, 1915. Serial No. 42,301.

To all whom it may concern:

Be it known that I, JAMES O. WATKINS, a citizen of the United States, and a resident of San Francisco, county of San Francisco, 5 State of California, have invented certain new and useful Improvements in Wireless Telegraphy, of which the following is a specification.

The invention relates to a receiving system for wireless telegraphy and especially to a device adapted to be used in said system.

An object of the invention is to provide an apparatus by means of which continuous 15 electrical oscillations of high frequency are converted into continuous oscillations of lower frequency.

The invention possesses other objects and advantageous features, some of which, with 20 the foregoing, will be set forth at length in the following description, where I shall outline in full that form of the invention which I have selected for illustration in the drawings accompanying and forming part of the 25 present specification. In the drawings I have shown only one specific form of the apparatus of my invention, but it is to be understood that I do not limit myself to such form, because my invention may be embodied in a multiplicity of forms, each being 30 a species of my said invention. It is also to be understood that by the claims succeeding the description of my invention, I desire to cover the invention in whatever form it may 35 be embodied.

Referring to said drawings:

Figure 1 is a top or plan view of one form of the apparatus of my invention.

Fig. 2 is a vertical section taken on the 40 line A—A Fig. 1.

Fig. 3 is a diagrammatic representation of a wireless telegraphy receiving circuit, showing the apparatus of my invention arranged therein.

45 Fig. 4 is a diagrammatic illustration of the effects produced by the operation of the apparatus.

The frequency of the oscillations of the electric impulses in a wireless telegraphy 50 system employing substantially continuous undamped waves, is so high that they cannot be directly utilized to operate electro magnetic instruments, such as telephone receivers, to produce audible signals. The

frequency of the received oscillations is 55 above the limits of audibility and to be received by the ear, the frequency must be reduced to within the limits of audibility. This has been accomplished heretofore by arranging an interrupter and a condenser in 60 the receiving circuit, the condenser being charged by the high frequency oscillations during the time that the interrupter is closed, and discharging with a surge through the telephone receivers when the interrupter 65 is open.

In accordance with the present invention, the high frequency current is converted into a low frequency current, and the telephone receivers are operated by the latter current. 70 The receiving circuit is opened and closed at a frequency which may be made to approach synchronism with the frequency of the received oscillations, thereby producing a low beat frequency. The regularity of the beat 75 frequency gives a musical note to the received signals and the nearer the frequency of interruption approaches the frequency of the incoming waves, the lower will be the note. In Fig. 4 I have shown diagrammatically the incoming undamped oscillations of high frequency 2. The frequency of interruption is somewhat less than the frequency 80 of the waves, resulting in beat frequency oscillations 3, which are of much 85 lower frequency than the incoming waves.

The apparatus of my invention comprises a suitable base 4, upon which is mounted a metallic standard 5. Secured to the standard 5 is a holder 6 having a resilient shank 90 7. Horizontally disposed in the holder 6 is a bar 8 which constitutes the base of the string or wire holder. Passing through the standard 5 is an adjusting screw 9 which bears against the holder 6, and by turning 95 the screw the position of the bar 8 may be varied.

Secured to the bar at one end is a block 12 to which one end of the wire 13 is secured, and at the other end of the bar is a 100 slotted post 14 through which the wire passes. The other end of the wire is fastened to the key 15 engaging in the end of the bar. Adjacent post 14 is a second slotted post 16 having a roller 17 under which the 105 wire passes arranged in the slot. Between the posts and guided thereby is a means for varying the tension of the wire. This means

consists of a wedge shaped block 18 guided by the posts 14 and 16 and being movable against the wire by the thumb screw 19 passing through the bar 8.

5 The wire is vibrated by means of a smooth edged disk 21 which rotates in interrupted engagement with the wire. The point of contact of the disk and wire is arranged with relation to the wire, so that it occurs 10 at an anti-node of the desired harmonic. The wire adheres to the disk as it rotates and is stretched out until the curvature of the disk allows it to slip back to its former position, where it is again caught by the disk 15 and the action repeated. Vibration of the wire will, therefore, be maintained and the wire contacts with the disk at the frequency of its vibration. The axis of the disk preferably lies in the same horizontal plane as 20 the wire and the disk is rotated in such direction that that side of the disk which contacts with the wire moves upward.

The disk is placed in contact with the wire at a point midway between two successive nodes or in other words, at a point exactly one-half the distance between two nodes. Means are, therefore, provided for adjusting the point of contact with relation to the adjacent nodal points. This adjustment is accomplished by means of the sliding bridge 22 which rests on the bar 8 and which engages the wire. A thumb screw 23 is provided for sliding the bridge along the bar 8. After the proper position of the 30 bridge is found which produces the proper distance between the disk and the effective end of the wire, tuning may be accomplished by varying the tension of the wire by means of the screw 19 or by varying the pressure 35 of the wire against the disk by means of the screw 9. The disk is rotated by a motor 24 which is insulated from the wire 13.

I have found that the adjustment of the apparatus usually holds better if the disk is 45 not rotated exactly at right angles to the wire, but preferably at an angle of about 80° with respect thereto.

The device is placed in the receiving circuit in series with the telephone receivers 25 50 the wire 13 being connected in the circuit by means of the binding post 26 and the disk being provided with a brush 27 connected to the other side of the circuit. The incoming high frequency currents pass through the 55 disk and wire in series and are interrupted at the frequency of the harmonic producing a beat wave of low frequency which passes through the telephones.

The disk, which is preferably made of 60 phosphor bronze, bears lightly against the wire, which is preferably of steel. The edge of the disk, which is preferably rounded, should be very carefully polished with crocus cloth and should be kept clean 65 and dry in order that the frequency of in-

terruptions may be constant. It is essential also that the edge of the disk be concentric with its axis of revolution.

By making the frequency of vibration of the wire equal to the frequency of the oscillations, the device may be employed as a 75 rectifier.

I claim:

1. In an apparatus of the character described, an electric circuit, a stretched wire 75 mounted to vibrate and a smooth edged rotatable disk in contact with said wire said wire and said disk being connected in series in said circuit.

2. In an apparatus of the character described, an electric circuit, a wire mounted to vibrate and a smooth edged rotatable disk in contact with said wire at an antinode said wire and said disk being connected in series in said circuit. 85

3. In an apparatus of the character described, an electric circuit, a stretched wire mounted to vibrate and a smooth edged rotatable disk in light contact with said wire at an antinode adjacent the end of the wire 90 said wire and said disk being connected in series in said circuit.

4. In an apparatus of the character described, an electric circuit, a stretched wire mounted to vibrate, a smooth edged rotatable 95 disk in contact with said wire and means for varying the tension of said wire said wire and said disk being connected in series in said circuit.

5. In an apparatus of the character described, an electric circuit, a stretched wire mounted to vibrate, a smooth faced rotatable disk in contact with said wire at an antinode and means for varying the tension of 100 said wire said wire and said disk being connected in series in said circuit. 105

6. In an apparatus of the character described, an electric circuit, a stretched wire mounted to vibrate, a smooth edged rotatable disk in contact with said wire and means for 110 varying the pressure of the wire against the disk said wire and said disk being connected in series in said circuit.

7. In an apparatus of the character described, an electric circuit, a stretched wire 115 mounted to vibrate, a smooth edged rotatable disk in contact with said wire at an antinode and means for varying the pressure of the wire against the disk said wire and said disk being connected in series in said circuit. 120

8. In an apparatus of the character described, an electric circuit, a stretched wire mounted to vibrate, a smooth edged rotatable disk in contact with said wire and means for varying the vibratory length of said wire 125 said wire and said disk being connected in series in said circuit.

9. In an apparatus of the character described, an electric circuit, a stretched wire mounted to vibrate, a smooth edged rotatable 130

disk in contact with said wire at an antinode and means for varying the vibratory length of said wire said wire and said disk being connected in series in said circuit.

5 10. In an apparatus of the character described, an electric circuit, a stretched wire mounted to vibrate, a smooth edged rotatable disk in contact with said wire at an antinode adjacent one end of the wire and means at 10 the same end of the wire for varying the vibratory length of the wire said wire and said disk being connected in series in said circuit.

11. In an apparatus of the character described, an electric circuit, a stretched wire mounted to vibrate, a smooth edged rotatable disk in contact with the wire at an antinode, means for varying the tension of said wire and means for varying the pressure of said 20 wire against the disk said wire and said disk being connected in series in said circuit.

12. In an apparatus of the character described, an electric circuit, a stretched wire mounted to vibrate, a smooth edged rotatable disk in contact with said wire at an antinode, means for varying the vibratory length of 25 said wire, and means for varying the tension

of said wire said wire and said disk being connected in series in said circuit.

13. In an apparatus of the character de- 30 scribed, an electric circuit, a stretched wire mounted to vibrate, a smooth edged rotatable disk in contact with said wire at an antinode, means for varying the vibratory length of said wire and means for varying the pres- 35 sure of the wire against the disk said wire and said disk being connected in series in said circuit.

14. In an apparatus of the character de- 40 scribed, an electric circuit, a horizontally disposed stretched wire mounted to vibrate and a smooth edged disk rotatable about a horizontal axis lying in the same horizontal plane as the wire, in contact with said wire at an antinode said wire and said disk being 45 connected in series in said circuit.

In testimony whereof, I have hereunto set my hand at Honolulu, Territory of Hawaii, this 10th day of June, 1915.

JAMES O. WATKINS.
